UNITED STATES PATENT OFFICE

AARON BENOWITZ, OF NEW YORK, N. Y., ASSIGNOR, BY MESNE ASSIGNMENTS, TO
SYNTHETIC FUR MILLS CORP. OF NEW YORK, N. Y., A CORPORATION OF NEW YORK

PROCESS FOR MANUFACTURING A TRIMMING MATERIAL OR CLOTH

Application filed August 11, 1931. Serial No. 556,342.

This invention relates to a new and useful process of providing by hand or manufacture a trimming material or cloth, hand woven, or manufactured.

5 The said trimming material or cloth is rather unique in appearance, very durable, and easy to make, as the latter may be produced by hand, or by machine.

As the process involved is comparatively 10 simple the cost of manufacturing should be proportionately low.

With the above and other objects in view, this invention consists of the novel features of construction, combination and arrangement of parts, hereinafter fully described, claimed and illustrated in the accompanying drawing forming parts of this application, and in which similar characters of reference indicate corresponding parts in all views, and in which:

20 Figure 1 is a top plan of my finished fabric;

Figure 2 is a transverse sectional view taken on line 2—2 of Figure 1;

Figure 3 illustrates one of the preferred 25 modes of making the said trimming material or cloth; while

Figure 4 shows another mode; and

Figure 5 illustrates a somewhat different manner of procedure;

30 Figure 6 is a bottom view of the cylinder 15 shown in Figure 5.

Referring more particularly to the drawing, 10 indicates a piece of material, preferably card clothing provided with the usual 35 fine wire threads 11, scattered over the surface.

On top of the said card clothing, which has the advantage that it may be of any desired size, a chenille 12, or any other suitable kind 40 of yarn, is then laid out by means of the said wires 11,—according to a prearranged design, or the operator's own design, which may be simultaneously conceived,—in such a manner that the said yarn or chenille will 45 form a compact unity, or mass of cloth-like material, which is to constitute the upper, or front surface of the said trimming material or cloth, as shown at 13 in Figure 2.

After the said front surface material has 50 thus been arranged, and while the latter is

still held in place upon and retained by the wires of the card clothing, a rubberized cloth is next laid upon the top of the said surface material, and a slight pressure applied thereto, whereupon the latter with the said rubberized cloth, shown at 14 in Figure 2, which is to form the bottom or lower part of the finished product, may be lifted clear of the wires of the said card clothing. If further desired, in order to secure absolute adhesiveness between the design, as laid out, and the rubberized material, these two parts may be subjected to a slight pressing process.

The said trimming material or cloth may also be made in the following slightly different manner:

A large table, shown in Figure 4, has upon its top-surface been provided with a suitable design for the said trimming material or cloth; this design may be made upon the said 70 surface in any suitable manner, as by chalk, lead pencil, etc.; a chemical fluid of a slightly adhesive characteristic, is next applied to the said top-surface, and the yarn or chenille is then laid out upon the said table according to the design; the said yarn being secured in the laid out and arranged position by means of the said fluid.

When thus, as formerly described, a compact unity, or mass of cloth-like material has 80 been obtained from the said chenille or yarn, a rubberized cloth is in turn applied to the top surface of the said material, and a slight pressure exerted, whereupon the ensemble, i. e., the trimming proper and rubberized cloth, may readily be disengaged from the table, and thus another finished product of trimming material or cloth will have been 85 provided.

It is obvious that instead of the said fluid, a number of adhesive tapes may be stretched across the table to secure the chenille or yarn in position without in any manner interfering materially with the design, even if the latter is prearranged and marked upon the 90 table.

In Figure 5 is shown a mechanical embodiment of my idea, which may be employed to some advantage.

Thus a cylindrical tube 15 is herein pro-

vided with a piston 16; the said tube being near the bottom and oppositely formed with openings 17, adapted to let the chenille or yarn pass through, while the latter by means of the piston is pressed into and fastened upon a rubberized cloth 14 arranged below the said tube, thereby providing a result similar to one of these formerly described.

- The usual means may be employed for 10 moving the yarn or chenille, and the said tube may be movable and suitable for manipulation by hand; or the said tube may be stationary and the rubberized cloth may be moved underneath the former.
- 15 While the said tube-device may be modified in construction in various ways, as it is only desired herein to indicate the principles, the said tube may be operated by electricity; and instead of a piston, as shown, compressed 20 air may well be used.

A bottom construction of the said tube is shown in Figure 6.

It is quite obvious that changes may be made in the form, construction and arrangement of the several parts, as shown, within the scope of the appended claims, without departing from the spirit of the invention, and I do not therefore wish to limit myself to the exact construction and arrangement 30 shown and described herein.

What I claim as new, and desire to secure by Letters Patent of the United States, is:

1. A process of producing trimming material or cloth, hand woven, or manufactured 35 comprising the steps of using a card clothing provided with fine wire threads, the lay out, according to a preconceived design, of a chenille or other suitable yarn between the said wire threads in a compact manner to form a 40 cloth-like material, and attaching to the latter, by placing on top thereof and exerting a slight pressure, a rubberized cloth, substantially as shown and described.

2. A process of producing trimming material or cloth, hand woven, or manufactured, 45 comprising the steps of using a card clothing provided with fine wire threads, the lay out, according to a design, of a yarn or chenille between said wire threads in a compact manner to form a cloth-like material, and attaching 50 to the latter, by placing on top thereof and exerting a slight pressure, a rubberized cloth, whereupon the said ensemble, when disengaged from the said card clothing is 55 submitted to a slight pressing, substantially as shown and described.

Signed at New York City, in the county of New York and State of New York, this 3rd day of August, A. D. 1931.
